UNITED STATES PATENT OFFICE.

PRESTON FOWLER, OF GORDON, NEBRASKA.

AUXILIARY AIR VALVE.

Application filed March 2, 1921. Serial No. 449,068.

To all whom it may concern:

Be it known that I, PRESTON FOWLER, a citizen of the United States, residing at Gordon, in the county of Sheridan and State 5 of Nebraska, have invented certain new and useful Improvements in Auxiliary Air Valves, of which the following is a specification.

This invention relates to the means for admitting fuel to internal combustion engines and has special reference to the engines of automobiles. The object of the invention is to provide a valve between the carbureter and the intake manifold by the manipulation of which an additional supply of air may be admitted to the manifold and the consumption of fuel thereby reduced. Other objects of the invention will appear in the course of the following 20 description.

The invention is illustrated in the accompanying drawings, in which—

Figure 1 is an elevation of the improved valve in position in the conduit leading from the carbureter to the intake manifold;

Fig. 2 is an enlarged vertical section through the valve;

Fig. 3 is a plan view of the valve, the valve proper being removed.

In the drawings, the reference numeral 1 denotes the intake manifold of an automobile motor and 2 the carbureter cooperating therewith. In carrying out my invention, I interpose in the pipe 3, leading 30 from the carbureter to the manifold, a valve casing 4 having a passage therethrough which communicates with and forms a continuation of the passage from the carbureter to the manifold. On its under side this 35 valve casing 4 is provided with a cylindrical extension 5 and within the said cylindrical extension a hollow cylindrical valve body 6 is slidably mounted. The lower end of the bore of the cylindrical extension is closed 40 by a plug 7 provided with notches 8 or otherwise constructed so that it may be engaged by a suitable turning tool. Alined with the extension 5, on the upper side of the valve casing, is an annular flange or 45 rib 9 constituting a valve seat, the upper edge of said rib or flange being beveled, as clearly shown in Fig. 3. The valve proper 50 consists of a plate or disk 10 having its edge suitably beveled to rest upon the beveled 55 edge of the seat or rib 9 and these beveled surfaces are preferably finished so as to provide a ground joint. The disk or valve plate 10 is carried by a stem 11 which has its lower end threaded into a boss 12 on the bottom of the cylindrical valve 6 and a spring 13 is coiled around the said stem 60 between the bottom of the valve 6 and spaced abutments 14 which extend across the opening defined by the inner wall of the rib 9, it being readily understood, as 65 shown in Fig. 2, that the rib or valve seat 9 defines an opening axially alined with the bore of the cylindrical extension 5 and communicating with the passage through the main valve casing 4. To the upper end of 70 the valve stem 11, I secure a link 15 which has its upper end pivoted to one arm of an angle lever 16 fulcrumed upon the manifold 1 or upon any other convenient support, the 75 arm of said lever remote from the link 15 extending upwardly, as shown clearly in Fig. 1. The upwardly extending arm of the lever 16 is connected by a link or rod 17 with a pedal or hand lever 18 mounted upon the dash 19 of the automobile. 80

Normally, the spring 13 is expanded between the abutments 14 and the bottom of the valve 6 so that the said valve 6 is housed within the cylindrical extension 5 and the valve 10 is seated, the passage through the 85 valve body 4 being uninterrupted so that fuel may flow freely from the carbureter to the intake manifold. Should the vehicle strike a smooth level road while traveling at high speed, the chauffeur by manipulating the pedal or other controlling member 18 will turn the angle lever 16 about its fulcrum and thereby raise the valve stem 11 against the tension of the spring 13 so that the valve 10 will be unseated and the valve 90 95 100 105 110

6 will be caused to project more or less across the passage through the valve body 4. The flow of fuel will thus be partly cut-off and an extra supply of fresh air will be admitted into the valve casing 4 to commingle with the fuel so that the mixture will be thinned and an economy of fuel effected. If the valve body 6 be raised a considerable extent, it will be possible to so reduce the flow of fuel that practically no carburetted mixture will pass to the engine and it will receive a vast preponderance of cool air so that it will be cooled and partially braked by working against the cool air. If the vehicle should be traveling down hill and 110

acquire an undesirable velocity, the device may be manipulated so that the valve body 6 will be raised entirely across the passage through the body 4 and the flow of fuel and air entirely cut-off whereupon the travel of the car will keep the engine turning over and working against a partial vacuum in each cylinder so that it will act as a vacuum brake. When the hold upon the controlling member 18 is released, the spring 13 at once expands and reseats the valve 10, the valve body 6 being withdrawn from across the passage through the body 4 and serving as a dash pot within the cylindrical extension 5 to prevent the seating of the valve 10 being accomplished in such a forcible manner as might tend to bend or otherwise damage the same. The device is obviously simple in construction and operation and it may be applied to any combustion engine without great expense and without requiring a dis-

assembling of the parts or any substantial change in the construction of the same.

Having thus described the invention, what is claimed as new is:

A device for the purpose set forth comprising a valve casing having a passage therethrough and an inlet opening in one side, an extension on the opposite side of the valve casing, a hollow cylindrical valve 30 slidably mounted in said extension, a valve adapted to close the inlet opening, an abutment extending across the inlet opening, a stem rigidly connecting the hollow cylindrical valve and the second-mentioned valve, 35 means for manipulating said valve stem, and an expansion spring coiled around the valve stem between the abutment and the bottom of the hollow cylindrical valve.

In testimony whereof I affix my signature.

PRESTON FOWLER. [L. S.]
